(57) **CLAIM**

The ornamental design for a fin as shown and described.

DESCRIPTION

FIG. 1 is a perspective view of a fin in accordance with a first embodiment of our design;

FIG. 2 is a front elevational view of the fin of FIG. 1;

FIG. 3 is a rear elevational view of the fin of FIG. 1;

FIG. 4 is a left side elevational view of the fin of FIG. 1;

FIG. 5 is a right side elevational view of the fin of FIG. 1;

FIG. 6 is a top plan view of the fin of FIG. 1;

FIG. 7 is a bottom plan view of the fin of FIG. 1;

FIG. 8 is a perspective view of a fin in accordance with a second embodiment of our design;

FIG. 9 is a front elevational view of the fin of FIG. 8;

FIG. 10 is a rear elevational view of the fin of FIG. 8;

FIG. 11 is a left side elevational view of the fin of FIG. 8;

FIG. 12 is a right side elevational view of the fin of FIG. 8;

FIG. 13 is a top plan view of the fin of FIG. 8;

FIG. 14 is a bottom plan view of the fin of FIG. 8;

FIG. 15 is a perspective view of a fin in accordance with a third embodiment of our design;

FIG. 16 is a front elevational view of the fin of FIG. 15;

FIG. 17 is a rear elevational view of the fin of FIG. 15;

FIG. 18 is a left side elevational view of the fin of FIG. 15;

FIG. 19 is a right side elevational view of the fin of FIG. 15;

FIG. 20 is a top plan view of the fin of FIG. 15; and,

FIG. 21 is a bottom plan view of the fin of FIG. 15.

The broken lines having alternating length dash lengths (long dash-short dash-long dash) in FIGS. 7, 14, and 21 delineate portions of the fin that do and portions of the fin that do not form part of the claimed design.

1 Claim, 21 Drawing Sheets
